PRESSURE REGULATOR

Alexander Boynton, San Antonio, Tex., assignor
to Chas. A. Beatty, San Antonio, Tex.

Application September 30, 1932, Serial No. 635,540

7 Claims. (Cl. 50—23)

My invention relates to pressure regulators and has particular reference to regulators for providing a uniform pressure within a fluid conducting line or container.

5 It is an object of the invention to provide an automatically operating device by means of which a control valve may be moved to allow the entrance to a line or container of a certain maximum fluid pressure.

10 I desire to provide a device of this character which will operate accurately and which will be sensitive to changes in pressure and which will be enabled to adapt itself to changes in pressure so as to maintain the pressure uniform in the device and its discharge pipe.

15 Another object of the invention is to provide a device of this character which is simple in construction and which will not easily get out of order in use.

20 I further desire to provide a structure of this character which may be set for pressures of different value and which will be capable of operation under both high and low pressures on the intake side and be capable of adjustment to accommodate the particular pressure which is to be permitted on the discharge side.

The invention resides in the particular construction and arrangement of the parts making up the invention, all of which will be more clearly understood from the description which follows:

30 In the drawing herewith, Fig. 1 is a central longitudinal section through a conducting line having my invention installed therein.

Fig. 2 is a similar sectional view through the 35 inlet end of said device, said view being taken at right angles to the view shown in Fig. 1.

Fig. 3 is a transverse section on the plane 3—3 of Fig. 1; and

Fig. 4 is a similar transverse section on the plane 4—4 of Fig. 2.

40 In the drawing I have shown my device as being installed within a housing 16, which forms a part of a conducting line. The upper end of the housing is connected with a T-shaped fitting 15, having a lateral port connected by means of the L 19 to the discharge flow line 20. The upper end of the fitting 15 has a threaded opening therein to receive the plug 5 which forms a guide for the stem 4, rotatable therein. The plug 5 is formed 45 with a recess in the outer end of the same to receive packing adapted to be compressed by the gland 3, movable through the tightening of the cap 2 upon the threaded outer end of the plug. Between the plug and the outer wall of the T-shaped fitting I have undercut a shoulder into

which is fitted a washer 21, which may be of compressible material such as lead forming a seal around the threaded connection between the plug and the T-shaped fitting.

5 The stem 4 has a handle at its outer end whereby it may be rotated. Its inner end projects through the plug and is formed with a squared head 4a fitting within a socket 22 in the nipple 6 upon the valve adjusting assembly. The squared head 4a is slideable within the socket 22 and, by the rotation thereof, the nipple may be screwed into or from a threaded connection at 23 with the valve carrier 12.

The valve carrier 12 is an elongated sleeve, 15 which has at its lower end a diametrical cross arm 24, which is adapted to fit slidably between two upright arms 25 upon the valve seat member 13. The cross arm has a threaded opening axially of the sleeve 12 to receive the shank 26 of the valve 20 carrier 11, which projects downwardly from the cross arm.

20 With the housing formed by the sleeve 12 is the expanding bellows 27, which forms a closed diaphragm adapted by its expansion and contraction to regulate the position of the valve. The 25 bellows member shown is made up of a wall of thin resilient metal, which is preferably a two or three-ply wall, for the reason that this construction is somewhat more compressible and more durable than a single ply wall. The metal making 30 up the bellows is strong resilient metal. I have shown the corrugations on the wall of the bellows as extending spirally around the wall of the tube which constitutes the bellows. This form is employed for the purposes of economy, it being also 35 common to employ bellows made up of ring-shaped corrugations.

The upper end of the bellows is connected by welding or soldering to the flange upon the connecting member 7. Said member is a circular disc with the downwardly projecting flange thereon previously mentioned. It also has a central inwardly extending boss to accommodate a threaded socket 28 to receive the lower threaded end of the screw 10.

45 The screw 10 has its head projecting upwardly into the squared socket 22, the said head projecting very slightly above the wall which closes the inner end of said socket. It has an enlarged upper end, which has a slight clearance relative 50 to the wall of the socket and has a shoulder bearing against the upper end of the connecting member 7. It is to be noted that, when the shoulder is in contact with the connecting member, the head of the screw has a slight clearance 55

above the wall of the socket, thus forming a swivel connection between the connecting member 7 and the valve adjusting plug or nipple 6. In this way it is possible to screw the plug or nipple, 5 upwardly or downwardly in the sleeve 12 to adjust the valve, without the necessity of rotating the bellows member.

The lower end of the bellows is also connected by welding or soldering to an upwardly extending flange 29 upon the bottom end connection 8 for the bellows. The said bottom connecting member is of annular shape and is threaded at its lower end to receive the base connection 30. Said base connection is a plug-shaped nut having a lower threaded shank 9 for engagement with the arms 25 upon the base holder 13. There is a small channel or duct, shown at 31, formed in the upper end of this plug to allow the passage of liquid from the interior of the bellows. 10 It is my intention to connect the plug rigidly in position when the device has been assembled and to connect the plug with the bottom end connection 8 by means of solder or welding material shown at 32.

25 Within the bellows, and compressed slightly between the upper and lower end connections, is a spiral spring 18. This spring tends to hold the bellows in a predetermined extended position, as will be later described.

30 The valve seat member 13 has a lower ring shaped end threaded on its outer surface to screw within the inner wall of the casing 16. It has countersunk openings 33 on its lower side to accommodate a wrench, by means of which it 35 may be screwed in position with the arms 25 thereon extending upwardly into the sleeve 12. As will be seen from Fig. 4, the two arms 25 are circular on their outer side to fit within the sleeve and have a diametrical slot between them

40 to receive the transverse connecting arms 24 upon the sleeve 12. The upper ends of the arms abut against the lower side of the plug 30 and are threaded to receive the lower shank 9 on said plug. It will be seen that this connection 45 has the effect of anchoring the lower end of the bellows member to the lower end of the casing 16 of the flow line. Furthermore, the sleeve 12 is held against rotation relative thereto so that the upper valve-adjusting plug 6 may be adjusted.

50 The ring 13 has a passage axially therethrough, the inner side of which is rounded to form a seat for the valve 11. The passage through the ring is the inlet for fluid such as gas passing through the casing.

55 Below the valve seat member 13 I employ a lock nut 14 adapted to compress a washer 34 against the lower end of the valve seat member and to lock the same from unscrewing. The opening through the nut is formed with a stream line contour to accommodate fluid passing in toward the valve.

60 I may place a pressure indicator 35 of ordinary construction upon the upper T 15 of the assembly housing so that the fluid pressure within the line may be determined at any time.

65 In the operation of my device the fluid, such as gas, will pass through the line, entering below the valve and passing out through the connecting line 28. In its passage through the casing 16 it will find free access into the sleeve 12 and about the bellows assembly and will exert a pressure thereon.

70 The bellows will be assembled by turning the lower end thereof upwardly before the plug 30 has been screwed in position. The spring will be

7 inserted in place and the bellows will then be filled with a liquid such as glycerine. After being thus filled, the bellows will be compressed longitudinally to the maximum amount which it is contemplated it will be compressed in use. This will force some of the glycerine out through the passage 31. The pressure will then be released and the spring will again extend the bellows, but not quite to its original extent, there being a small permanent set developed in the 10 bellows, due to its compression. The spring will be under slightly more tension than it was before the compression. The plug after being tightened in position will be soldered in place and the passage 31 for the glycerine will be closed. 15 It will thus be seen that during operation the interior of the bellows member will be nearly filled with glycerine, the remaining portion being filled with air. The plug may, however, be tightened and soldered before the bellows is allowed 20 to expand. In such case a vacuum will result above the glycerine.

When the device is to be operated the handle 4 will be used to screw the bellows assembly up or down as is necessary to adjust the valve 25 11 to the proper position to allow sufficient gas to enter to maintain the desired pressure in the casing. Thereafter, the operation of the device will be automatic. If the pressure in the line increases unduly the effect will be to compress 30 the diaphragm or bellows member longitudinally and as the lower end is anchored in position the upper end will be drawn downwardly, forcing the sleeve 12, with the valve thereon, downwardly also so as to move the valve toward closed 35 position and to constrict the passage through which the fluid is entering. By thus restricting the passage of the fluid the pressure inside will be decreased and the predetermined pressure within the casing will be maintained. It is obvious that if the reverse condition was set up in the casing, that is, if the pressure was lowered therein beyond the desired amount, the result would be to allow the bellows to expand slightly with a result that the valve would be 40 opened to allow the entrance of a larger proportion of the pressure fluid.

45 My device is adapted particularly for use in handling gas and to preserve in a branch line a pressure which may be materially lower than 50 that in the main line. This may be employed, for example, in a line running from a gas well, where the pressure is high, to a gas main from which gas is consumed. The pressure in the main line may be preserved at a value considerably lower than that from the well. It will be obvious that the pressure may be stepped down between any two conducting lines or containers so that the proper pressure may be had in the line of the consumer, whether in industrial 55 establishments or for home consumption. It will find a general application in many different lines conveying gases or liquids.

55 By employing a liquid, such as glycerine, within the bellows member during its operation, I am 60 enabled to handle what would ordinarily be considered excessively high pressures. The presence of the liquid within the bellows or diaphragm will prevent its collapsing under extreme pressure. The amount of compression of the 65 bellows will be limited by the length of the air pocket or vacuum, as the case may be, above the liquid remaining in the bellows, which will ordinarily be small, compared to the total length of the bellows. I am enabled to handle pres- 70 75

sures of five thousand pounds per square inch, with a wall thickness of the bellows or diaphragm of .008 of an inch, and where the wall thickness is increased to .030 of an inch, hydraulic pressures to the amount of ten thousand pounds per square inch have been handled without impairing the apparatus.

It will be obvious that the arrangement of my apparatus will permit the control of pressures in lines with a high degree of accuracy and that when once properly set and calibrated, my device will control pressures in the conducting line so that they will be maintained within a certain maximum pressure which may be predetermined. The device is simple in construction and will not easily get out of order. The further advantages of the device will be obvious to those skilled in the art.

What is claimed as new is:

- 20 1. A pressure regulator including a fluid-conducting casing having an inlet at one end and an outlet at the other end, a longitudinally extensible support in said casing, a valve on said support in said inlet, means at one end thereof to manually adjust said support and said valve relative to said inlet, means to anchor the opposite end of said support, said valve being automatically adjustable by the longitudinal movement of said support in response to the pressure 25 of fluid passing through said casing to maintain a predetermined fluid pressure in said casing.
- 25 2. A pressure regulator including a casing having an inlet and an outlet for fluid under pressure, a bellows-shaped support, a valve at one end of said support projecting into said inlet, means to yieldably hold said support in extended position and means to anchor the end of said support adjacent said valve, the walls of said support being compressible under fluid pressure in said casing 30 to move said valve relative to said inlet.
- 30 3. A pressure regulator including a casing having an inlet and an outlet for fluid under pressure, a bellows-shaped support, a valve at one end of said support projecting into said inlet, means to 35 yieldably hold said support in extended position,

liquid means to prevent excessive collapsing movement of said support under fluid pressure, and means to anchor the end of said support adjacent said valve, the walls of said support being compressible under fluid pressure in said casing to move said valve relative to said inlet. 5

4. A valve control device for pressure regulators including a uniformly corrugated bellows of metal, means to seal the ends thereof, a spring within said bellows tending to hold said bellows extended, 10 means to anchor one end of said bellows, a valve on said bellows adjacent said anchor controlled through the movement of said bellows, and means to prevent undue collapsing of said bellows, comprising a liquid nearly filling the interior of said 15 bellows but leaving an air space therein when said bellows is normally operating.

5. A pressure regulator including a casing through which fluid under pressure may flow, an inlet thereto, a bellows-shaped metal support, a 20 valve thereon controlling said inlet, a spring to hold said bellows extended to close said valve, a charge of liquid sealed in said bellows, and means to anchor one end of said bellows in said 25 casing.

6. A pressure regulator including, a casing, an inlet to said casing, a valve seat in said inlet, a sleeve in said casing, a longitudinally compressible diaphragm in said sleeve, a longitudinally adjustable plug in said sleeve, a swivel engagement between said plug and said diaphragm, and a valve at the other end of said diaphragm adjacent said seat, said diaphragm being compressible in response to fluid pressure in said casing to control the position of said valve. 30 35

7. A pressure regulator including, a casing, an inlet to said casing, a valve seat in said inlet, a sleeve in said casing, a longitudinally compressible diaphragm in said sleeve, means to support said diaphragm at the upper end of said sleeve, and a 40 valve at the other end of said diaphragm adjacent said seat, said diaphragm being compressible in response to fluid pressure in said casing to control the position of said valve.

ALEXANDER BOYNTON. 45
